J. Proud.
Collar.

No. 56610.

Patented July 24, 1866.

UNITED STATES PATENT OFFICE.

JAMES PROUD, OF NEW YORK, N. Y.

IMPROVEMENT IN SHIRT-COLLAR ATTACHMENT.

Specification forming part of Letters Patent No. **56,610**, dated July 24, 1866.

To all whom it may concern:

Be it known that I, JAMES PROUD, of the city, county, and State of New York, have invented a new and Improved Fastening for Attaching Collars to the Neck-Bands of Shirts; and I do hereby declare that the following is a full, clear, and exact description thereof, which will enable others skilled in the art to make and use the same, reference being had to the accompanying drawings, forming part of this specification.

The present invention relates to a novel fastening for attaching or securing a collar to the neck-bands of shirts, whereby the soiling or injuring of the collar is prevented, and if a "turned-down collar," so called, it is not required to turn it up in order to secure it to the back button of the shirt-band, as is now the case, the advantages of which are obvious.

In accompanying plate of drawings my improved fastening for collars is illustrated, Figure 1 being a view of a collar with it applied thereto, and Fig. 2 a horizontal section taken in the plane of the line *x x*, Fig. 1, and in the direction of the length of the collar.

Similar letters of reference indicate like parts.

A in the drawings represents a shirt-collar, which may be made of linen or paper, to which collar, at the point of the same where the button-hole is made for buttoning it to the back button of the neck-band of a shirt, my improved fastening B is attached. This fastening consists of a plate, C, made of metal, hard vulcanized india-rubber, or other suitable material, with a circular-shaped or round opening, D, of a size corresponding, or nearly so,

to that of the button of the shirt, from one side of which opening D extends a narrow straight slot, E.

To the back of the plate C a pin, F, is hinged or pivoted in a similar manner to that of breast-pins, and an eye, G, is secured for holding the pin fastened. By this pin the plate C is fastened to the collar in such a position that the end of its slot removed from the circular opening will correspond to the position of the back button-hole of the collar, when by slipping the plate by its circular opening over the back button of the neck-band of the shirt, and then pulling the collar in the proper direction to bring the slot under the said button, if the ends of the collar are then buttoned to the front button of the shirt, the collar will be necessarily fastened thereto, as is obvious without any further explanation, the use of the plate C dispensing with the necessity of turning up the collar if a "turned-down collar," so called, is used, and preventing the soiling or injuring of the collar—two important desiderata and advantages—besides increasing the facility and ease with which the collar can be buttoned to and unbuttoned from the shirt.

I claim as new and desire to secure by Letters Patent—

The plate C, having opening D E and hooks F, made as described, for the purpose specified.

The above specification of my invention signed by me this 6th day of June, 1866.

JAMES PROUD.
